ABSTRACT OF THE DISCLOSURE

There is disclosed an apparatus for opening bottles, cans, containers, casks and the like which is of the type incorporating a needle which piercingly extends through the cork into the internal compartment of a bottle or the like. By means of this needle and through the action of a pump unit, air can be conveyed beneath the cork. According to the invention, the pump unit encompasses a piston member situated in a housing, this piston member being actuated by a lever member rotatably mounted in the housing. Furthermore, a can opener mechanism is arranged at a portion of the housing which faces away from the cork puller or removal mechanism. This can opener mechanism can be actuated by a rotary knob seated upon the shaft of a transport wheel.

BACKGROUND OF THE INVENTION

The present invention broadly relates to a multipurpose utensil and, in its more specific aspect, concerns a combination device or apparatus which serves to open bottles, cans, containers, casks, and similar type articles. The inventive combination device is of the type incorporating a needle which extends through the cork into the interior of a bottle, by means of which air can be pumped through the action of a pump unit beneath the cork. In this manner, an overpressure is generated in the space between the level of the liquid in the bottle and the inner edge of the cork which, when it is sufficiently large, serves to lift the cork out of the bottle.

There are different types of physical constructions of devices known to the art by means of which it is possible through the action of a pump unit to pump air into the inside of a bottle through a needle tip which has been inserted through the cork into the interior of the bottle. However, it has been found that the previously known constructions possess certain drawbacks, because they fail to adequately accommodate to the particular characteristics of a bottle closure having a cork. A cork which has been properly inserted into the neck of the bottle generally forms a faultless, fluid-tight closure, but this is in no way intended to imply that such closure is also gas-tight. Now, it is known that when using cork puller mechanisms which operate according to the principle of injecting air into the bottle, it is not possible to build up sufficient pressure because the cork does not provide any gas-tight closure. The air which has been introduced into the space beneath the cork and above the level of the liquid in the bottle again escapes into the atmosphere and the cork retains an unchanged position at the bottle. This drawback could be compensated if sufficient air is quickly and in sufficient quantity introduced into the bottle. How-

2

ever, the pump unit is unfortunately designed such that it does not possess a sufficient pumping capacity.

On the other hand, sometimes it occurs that the cork adheres quite strongly to the neck of the bottle. Then, it is necessary to use a relatively high pressure, but the danger exists that the bottle itself will crack.

SUMMARY OF THE INVENTION

Accordingly, it is a primary objective of the present invention to provide an improved device for opening bottles, cans, containers, casks, and similar type articles, which effectively prevents the aforementioned drawbacks of the prior art constructions.

Another, more specific object of the present invention relates to an improved device of the type described which is capable of effectively removing a cork from a bottle in a safe and reliable manner.

A further significant object of the present invention relates to a combination device of the aforementioned type which provides, in a single unit, means for opening various types of containers or receptacles, such as bottles, cans, casks, and the like, with minimum effort.

A further object of the present invention relates to an improved combination device of the type described which is relatively simple in construction, extremely economical to manufacture, highly reliable in operation, and not readily subject to breakdown.

Now, in order to implement these and still further objects of the invention, which will become more readily apparent as the description proceeds, the invention contemplates that the pump unit incorporates a piston member which is disposed in a housing, such piston member being actuated by a lever member rotatably mounted at the housing. Additionally, a can opener mechanism is arranged at the portion of the housing which is facing away from the cork puller mechanism. This can opener mechanism can be actuated by a rotary knob or the like seated upon a shaft of a transport wheel.

BRIEF DESCRIPTION OF THE DRAWINGS

The invention will be better understood, and objects other than those set forth above, will become apparent, when consideration is given to the following detailed description thereof. Such description makes reference to the annexed drawing wherein:

FIG. 1 is a schematic front view of a preferred embodiment of inventive multipurpose utensil or combination device for opening bottles, cans, containers, casks, and similar type articles, incorporating a needle valve unit provided with a needle member which is mounted upon the graspable housing;

FIG. 2 is a longitudinal sectional view, taken through the graspable housing of the inventive combination device showing details of the pump unit and the actuation lever therefor;

FIG. 3 is a front view of the device shown in FIG. 1 as viewed from the opposite side thereof; however, with the needle valve and needle member removed as well as depicting the actuation lever locked flushly at the graspable housing, and further showing the can opener mechanism arranged at the lower portion of the graspable housing; and,

FIG. 4 is a side view, partly in section, taken through the graspable housing of the inventive device depicted in FIG. 2.

DESCRIPTION OF THE PREFERRED EMBODIMENTS

Describing now the drawings, in FIG. 1, reference numeral 1 designates the graspable housing or body member of the inventive device which can be conveniently held in the hand of the user. At one of the narrow sides 1a of the graspable housing 1, there is located a slot 1b out of which extends the actuation lever 2. This actuation lever 2 possesses a safety slide or catch 3 by means of which it is possible to fix the actuation lever 2 at the graspable housing 1, so that this lever bears flushly against the housing and closes the slit 1b appearing at the aforementioned narrow side 1a.

The inventive device further incorporates a cork puller or cork popping mechanism which, in the exemplary embodiment, comprises a needle valve unit 4 which can be threadably attached to the upper end face of the graspable housing 1, as best shown by referring to FIG. 1. Additionally, it will be seen that the needle valve unit 4 is provided with threading 5 at the side facing the needle member 6, by means of which the needle valve unit 4, if desired, can be threaded into the cork. The cork lifter or popping needle member 6 is mounted or located upon the needle valve unit 4.

Continuing, and by referring to FIG. 2, it will be recognized that a recess 11 is provided in the graspable housing 1, and a conical portion 12 and an elongate channel 13 communicated with the recess 11. During non-use of the cork puller mechanism, the needle valve unit 4, together with its needle member 6, are accommodated in the hollow compartment defined by the recess 11, the therewith merging conical portion 12, and the elongate channel 13 which, in turn, merges with the conical portion 12. Furthermore, located within the graspable housing 1 is a cylinder 14 which is closed by an insert member 15. A piston member 16 reciprocates within the cylinder 14, this piston member 16 extending downwardly to provide a piston rod 17. The piston member 16 and the piston rod 17 are provided with a longitudinally extending hollow bore 17a serving to receive a portion of a spring member 18. The other portion, namely, the upper portion of the spring member 18, is guided by a cylindrical projection 19 provided at the insert member 15. In the position of the spring member 18 shown in FIG. 2, it possesses a certain pre-stress or bias and urges the actuation lever 2 into its operational position. In order to secure the actuation lever 2 at the graspable housing 1, the safety catch or slide 3 is displaced into engagement with the bore 20 provided at the upper end face of the housing 1.

The insert member 15 possesses a threaded recess portion 21 at its upper face or end, into which the needle valve unit 4 can be threadably attached. The needle valve unit 4 operably communicates with the inner compartment of the cylinder 14 through the provision of the channels 22 and 23. A suction valve 24 is arranged at the piston rod 17, whereas the conventional pressure valve is provided at the needle valve unit 4 and is not visible in the drawings.

A link or lever member 25 is pivotably mounted at the piston rod 17 by a bolt member 26 or equivalent fastening expedient. The opposite end of this link member 25 is connected with the actuation lever 2 by means of a further bolt 27 or the like. This actuation lever 2 is mounted by means of a bolt member 28 in a bracket member 29. This bracket member 29 possesses a substantially U-shaped configuration, wherein the base portion 30 forms a downwardly extending closure portion and both of the bracket-like leg members 31 thereof extend upwardly. Both of these bracket-like leg members 31 of the bracket 29 form two walls in which there are mounted the bolt or shaft member 28 and the transport wheel 8 of the can opener mechanism. The actuation lever 2 is pivotably or rotatably mounted by means

of this bolt or shaft member 28. Additionally, the bracket-like leg members 31 are provided with slit means 32. A bolt member 33 piercingly extends through both of the slit means 32, such bolt member 33 being fixedly mounted in the wall portions of the graspable housing 1. Furthermore, the bolt member 33 piercingly extends through a recess or cutaway portion 34 provided at the actuation lever 2, this recess 34 possessing an approximately triangular configuration, as shown in FIG. 2.

In accordance with the invention, it should be recognized that a particularly large stroke is produced during the pumping operation which is composed of two components. In the one instance, there is a stroke which results due to the rotation or pivoting of the lever member 2 about the bolt member 28 and, on the other hand, a further stroke due to the lifting of the bracket member 29 until the bolt 33 is located in the lower position of the elongated slot 32. This partial stroke is provided in that during the movement of the actuation lever 2 the cutaway or recess portion 34 moves along the contour of the bolt 33.

Furthermore, it should be understood that the graspable housing 1 must possess a size which can be readily handled in convenient fashion, but, however, must be large enough so that still further utensils or devices can be accommodated thereat. Thus, in FIGS. 2 and 3, there is shown a can opener mechanism mounted at the lower portion of the graspable housing 1. The same actuation lever 2 which is used for the cork puller mechanism is also used to operate the can opener mechanism.

The can opener mechanism is located at the side or portion of the housing 1 which faces away from the cork puller mechanism previously described. This can opener mechanism embodies a transport wheel 8 and a cutting wheel 9. Instead of the cutting wheel 9, it would also be possible to use a stationary cutter. Cooperating with the transport wheel 8 and with the cutting wheel 9 are two roller members 10 which are arranged to each side of the cutting wheel 9, as best shown by referring to FIG. 3. Furthermore, by directing attention to FIG. 4, it will be recognized that the cutting wheel 9 is enclosed by a collar 49 which is inclined with respect to the walls of the graspable housing 1. The clamping rollers 10 which are arranged to each side of the cutting wheel 9 are rotatably mounted at the roller support 50. This roller support 50 is formed of sheet metal, or other suitable material, and bears against the wall of the grapsable housing 1 from the outside thereof and engages by means of two hook-shaped bent fingers or flaps 51 with a respective recess 52. Spring means 53 are arranged in the recesses 52, these spring means 53 acting as pressure springs which serve to press the roller support 50 against a stop means or member 54.

The transport wheel 8 of the can opener mechanism is arranged upon a shaft 37 which is rotatably mounted at the graspable housing 1. The end of this shaft member 37 which faces away from the transport wheel 8 extends out of the grapsable housing 1. Upon this protruding end of the transport wheel shaft 37, which end can be constructed in the form of a square bolt, there is secured a rotatable knob 58 which can be constructed in the manner of a wing nut.

The cork puller or lifter mechanism of the inventive device functions as follows: Initially, the security catch or slide 3 is retracted out of engagement with the bore 20 so that the operating or actuation lever arrives at the position shown in FIG. 2 under the action of the spring member 18. Consequently, the substantially U-shaped bracket 29 is displaced into the lower position depicted in FIG. 2, which is defined by the elongated slot 32 and the bolt member 33. Now, the needle valve mechanism 4 together with the cork popping needle 6 is removed from the hollow compartment defined by the components 11, 12 and 13 and is threaded into the threaded re-

cessed portion 21 of the upper end face of the insert member 15. The cork puller or cork popping device is now ready for operation. The needle 6 is then pushed through the cork of the bottle or the like, whereupon the one hand is used to carry out pumping motions by means of the operating or actuation lever 2. Thus, due to pressing of the actuation lever 2 against the graspable housing 1 the piston member 16 will be displaced until it reaches the lower end of the insert member 15. In so doing, the air is conveyed through the channels 22 and 23 via the pressure valve located in the needle valve unit 4, through the hollow needle 6, into the air compartment of the bottle to be opened. The pumping motion previously considered is continued for such time until sufficient pressure is available to pop out or remove the cork.

In the event that the cork cannot be removed in this manner, which could occur if the cork has not been sufficiently rigidly fixed into the bottle, then the threading 5 located at the needle valve unit 4 can be threaded into the cork. As a result, a sufficient sealing action is achieved so that also a satisfactory pressure can be generated for popping out the cork. However, the threading 5 of the needle valve unit 4 which has been threaded into the cork can be also advantageously used as a corkscrew in order to completely remove a cork which has not been entirely pulled out of the bottle.

The graspable housing 1, the operating actuation lever 2, the insert member 15, the needle valve unit 4, the piston 16 with its piston rod 17, and the link or lever 25, are all advantageously formed of a plastic possessing sufficient hardness. This renders possible, for instance, in the case of the piston member 16, that its sealing collar 16a can be formed of one piece together with the piston member 16.

The cork puller or lifter mechanism of the invention can be easily operated with one hand. It is sufficient to carry out movements with the actuation lever 2 in order to attain an effortless removal of the cork. Owing to the magnitude of the stroke of the piston member 16, which stroke is composed of two partial strokes, it is also possible to remove corks which are somewhat air permeable. In the case of corks which are more air permeable, the needle valve unit 4 together with its cork withdrawal threading 5 which faces the needle tip 6 is threaded to such an extent until the cork is positively sealed. Thereafter, the cork can be removed in the usual manner. But even with fixedly adhering corks, the withdrawal threading 5 provided at the needle valve unit 4 is of advantage. This cork withdrawal threading is used to assist the removal of the cork in that, on the one hand, due to the pumping in of air a pressure is exerted upon the cork and, on the other hand, by means of the withdrawal threading 5, the user pulls upon the cork just as with a normal cork puller. Owing to this double action which is exerted upon the cork, it is possible to practically remove every cork from a bottle.

The can opener mechanism provided at the inventive device functions as follows: Initially, the security bolt 3 is pushed back so that the lever arrives at the position depicted in FIG. 2 due to the action of a non-illustrated spring. In this position, in which the bracket member 29, and therefore, also the transport or drive wheel 8 is lowered, the cutting wheel 9 or the stationary cutter can be easily introduced into the inner edge of the can 56 (FIG. 4). Now, if the lever 2 is pressed against the housing 1 and retained therat, then the bracket member 29 is raised and remains, as long as the lever 2 is fixedly held at the housing 1, in the upper position, whereby the bolt 33 is located at the lower end of the slot 32. As shown in FIG. 3, in this position, the transport or drive wheel 8 engages beneath the cutting wheel 9. At the same time, the rollers 10 bear upon the indicated edge of the can and thus press the can, under the spring action of the springs 53, against the transport wheel 8, so that the can is positively entrained. Now, if by means of the

rotary knob 58 the transport wheel shaft 37 and, therefore, the transport wheel 8 is placed into motion, then, the can is opened. The transport wheel 8 possess a number of notches 60 at its periphery which are not symmetrical, rather are inclined towards one direction so that they intensely fixedly hook themselves in one direction at the can. They impart to the can opener mechanism particularly favorable properties, so that also cans with pronounced changes in direction or contour can be likewise opened without difficulty. Actuation by means of the rotatable knob 58 requires only very little force.

After the opening of a can, the actuation lever 2 is released, so that it assumes the position shown in FIG. 2. Consequently, at the same time, the bracket member 29 and, therefore, the transport wheel shaft 37 with the transport wheel 8 is lowered. Now, the can opener can be easily removed without difficulty from the can.

The graspable housing 1 permits the mounting of further devices, especially at the end face which is situated opposite to that end face required for the threadable mounting of the needle valve unit 4. Thus, it will be seen that at the lower end face 6 of the graspable housing 1, there is arranged a slide mechanism 41. This slide mechanism 41 travels in two grooves or ways 42 provided at the side walls of the graspable housing 1. Furthermore, slide mechanism 41 is provided with a structural steel member 43, which is flexed or bent at one side to form a tool 44 for opening bottles having a metal closure as well as bottle caps which can be cut and then lifted away. At the opposite end of the structural steel member 43 there is provided a portion which possesses a substantially triangular tip 45, this tip 45 being downwardly bent, as shown in FIG. 2. Thus, when the slide mechanism 41 is displaced to the left of FIG. 2, it is possible to use this tip portion 45 to press a pouring opening out of the bottom of a can or other type of cask or container. A screw 46 which is mounted at the slide mechanism 41 extends into a slot 47 so that the lateral displaceability of the slide mechanism 41 is conveniently limited. A spring member 48 generates a certain friction to thereby fixedly retain in this manner the slide mechanism 41 at the momentarily assumed operational position.

The slide mechanism 41 functions in the following manner: In order to open bottles which are sealed with a metal cap, the slide mechanism 41 is displaced into the right-hand terminal position of FIG. 2 until the screw 46 impacts against the edge of the slot 47. Now, it is possible to remove the metallic closures from the bottles. In so doing, operation of the actuation lever is not necessary, and therefore, it is advantageously brought to its rest position where it bears snuggly or flushly against the graspable housing 1 and retained in this position by means of the securing catch 3.

In the same position of the slide member 41 it is possible to use the working edge 44, which has been sharpened for this purpose, to cut away the head portion of a cap arranged over the neck of the bottle for protecting the cork. Then, the upper portion of the cap can be removed and the cork is rendered accessible for pulling out of the bottle.

If the slide mechanism or member 41 is placed into the left-hand terminal position, then the flexed or bent tip portion 45 can be pushed into the floor or bottom of cans and other casks or containers to provide a pouring or aeration opening.

A further possibility for cutting away a protective cap or hood from the bottle or the like is provided by the arrangement of a rotatably mounted cutting wheel 57 at the back of the actuation or operating lever 2. When this actuation lever 2 assumes its effectual or operable position, the cutting wheel 57 is located at the region of the graspable housing 1, shown in FIG. 2. The neck of the bottle is now placed and turned in the angular area defined by the intersection of the back or rear portion of the graspable housing 1 and the extended lever 2. Consequently, the

cutting wheel 57 cuts into the cap or hood enclosing the neck of the bottle which can then be removed. The cutting wheel 57 is advantageously formed of material which can be hardened to be glass hard, so that the cutting wheel 57 also does not tend to become dull even during intensive use. This manner of cutting away bottle cap closures or protective hoods or seals has proven itself to be exceptionally simple and easy to perform.

As already explained, the multipurpose utensil or combination device of the invention is essentially formed of plastic components. Only the elements which are intensively used or subjected to stress, such as the needle 6, the cutting wheels 9 and 57, the rollers 10, the roller support 50, the springs 53, 18 and 39, the transport wheel shaft 37, as well as a number of the bolts, are formed of partially hardened steel, for instance.

Should, nonetheless, it still not be possible to remove the cork, for instance, with especially permeable corks, by means of the combination of the generation of pressure beneath the cork and the pulling of the cork by means of the spiral-shaped threading at the needle valve unit 4, then, it would be possible to still provide a special cork puller of conventional construction at the graspable housing 1. This special cork puller can be threaded at the graspable housing 1 at the location of the needle valve unit 4 or at a different location of such graspable housing.

The operation of the can opener mechanism is also quite simple. Its operation is carried out independently of the cork puller mechanism owing to the actuation of the rotatable knob 58 arranged at the transport wheel shaft 37. With the transport wheel lowered, the graspable housing is held with one hand at the can and thereafter the lever is partially or completely placed against the housing. With the other hand, the transport wheel is placed into motion due to the subsequent actuation of the rotatable knob so that the opening of the can occurs.

It should be apparent from the foregoing detailed description that the objects set forth at the outset to the specification have been successfully achieved.

Accordingly, what is claimed is:

1. A device for opening bottles, cans, containers, casks, and the like, comprising a housing, a cork removal mechanism provided at said housing, said cork removal mechanism embodying needle valve means including a needle member capable of piercingly extending through a cork into the interior of a bottle, a pump unit for delivering air via said needle member beneath the cork, said pump unit including a piston member disposed at said housing, lever means pivotably mounted at said housing, serving to actuate said piston member, a can opener mechanism arranged at said housing at a region thereof facing away from said cork removal mechanism, said can opener mechanism including a transport wheel, a shaft member cooperating with said transport wheel, and a rotary knob seated upon said shaft member for actuating said can opener mechanism.

2. A device as defined in claim 1, wherein said lever means includes an actuation lever member, a pivot bolt for pivotably mounting said actuation lever member, the stroke of said piston member being composed of at least two partial strokes, one of which occurs due to rotation of said actuation lever member about said pivot bolt and the other of which occurs due to raising of said pivot bolt of said actuation lever member with respect to said housing through a predetermined amount.

3. A device as defined in claim 1, further including a bracket member mounted to be lengthwise displaceable in said housing, said lever means including an actuation lever member, said actuation lever member and said shaft member of said transport wheel of said can opener mechanism being rotatably mounted at said bracket member.

4. A device as defined in claim 3, further including means for mounting said bracket member so as to be

lengthwise displaceable in said housing, said mounting means incorporating slit means provided at said bracket member and a bolt member secured to said housing engaging with said slit, said bolt member cooperating with said slit to limit the lengthwise displaceability of said bracket member.

5. A device as defined in claim 4, wherein said actuation lever member is provided with a recess, said bolt member engaging with said recess and providing the guiding means for said actuation lever member, whereby upon application of said actuation lever member against said housing, said recess slides along the contour of said bolt member and thereby raises said bracket member.

6. A device as defined in claim 3, further including a pivot bolt for pivotably mounting said actuation lever member at said bracket member, said pivot bolt defining the axis of rotation of said actuation lever member in the upper position of said bracket member.

7. A device as defined in claim 1, wherein said rotary knob incorporates at least two wing portions which extend approximately radially with respect to the axis of said transport wheel, said rotary knob being provided with a bore disposed between said wing portions in order to mount said rotary knob upon said shaft member of said transport wheel.

8. A device as defined in claim 3, wherein said lengthwise displaceable bracket member is movable between an upper position and a lower position, and wherein the near upper position of said bracket member corresponds to the working position of the can opener mechanism and the lower position of said bracket member renders possible the introduction of the can opener at the can which is to be opened.

9. A device as defined in claim 1, further including a displaceable bracket member mounted at said housing, said shaft member for said transport wheel of said can opener mechanism being mounted at said bracket member.

10. A device as defined in claim 1, wherein said housing includes a hollow compartment for accommodating said needle valve means with its needle member, said needle valve means and housing having cooperating means for threadably connecting said needle valve means with its needle member in an operable position and for permitting detachment of said needle valve means and needle member during non-use thereof, wherein said needle valve means and needle member is accommodated in said hollow compartment of said housing.

11. A device as defined in claim 10, wherein said needle valve means is provided with cork withdrawal threading at the side thereof facing said needle member.

12. A device as defined in claim 1, wherein said housing includes a recess portion for retractably receiving said lever means during non-use, and means for fixedly retaining said lever means in its inoperable position at said housing.

13. A device as defined in claim 1, wherein said housing includes a narrow side portion, additional tool means displaceably mounted at said narrow side portion, said additional tool means including a tool member which is bent at one end and tapers into a point for pressing an opening in the cover of a can member, the opposite end of said tool member having a hook-shaped end portion for removing bottle closures and for cutting away bottle protective caps.

14. A device as defined in claim 1, wherein said can opener mechanism further includes a cutting element which is mounted at an inclination at said housing, and support rollers arranged at each side of said cutting element.

15. A device as defined in claim 14, wherein said cutting element comprises a cutting wheel.

16. A device as defined in claim 14, further including a roller support member secured flushly for lengthwise displacement at the exterior of said housing, said support

rollers being attached to said roller support member, and spring means acting upon said lengthwise displaceable roller support member and acting in the direction of said transport wheel.

17. A device as defined in claim 1, further including an additional cork puller of standard construction provided at said housing.

18. A device as defined in claim 1, further including an additional cork puller of standard construction which can be threadably attached to said housing instead of said needle valve means.

19. A device as defined in claim 1, wherein said lever means includes an actuation lever member having a back portion, a cutting wheel member mounted at said back portion of said actuation lever member, said cutting wheel member being rotatably arranged at said back portion

of said actuation lever member and being placed into an operable position when said actuation lever member is brought into its operable position externally of said housing in order to cut bottle closures or caps away from a bottle by means of said rotatable cutting wheel member.
